UNITED STATES PATENT OFFICE.

SAMUEL COHN, OF NEW YORK, N. Y.

MACHINE FOR GATHERING AND SEWING THE HEADS OF MANTLES.

No. 885,437.

Specification of Letters Patent.

Patented April 21, 1908.

Application filed November 22, 1901. Serial No. 63,302.

To all whom it may concern:

Be it known that I, SAMUEL COHN, a citizen of the United States, and residing in the borough of Manhattan, city, county, and State of New York, have invented certain new and useful Improvements in Machines for Gathering and Sewing the Heads of Mantles, of which the following is a specification.

My invention relates to machines for gathering and sewing the heads of mantles and has for its object to produce a machine which will gather and sew mantle heads, but it is also adapted to gather and sew the mouths of bags and other tubular structures.

In U. S. Letters Patent No. 678,542, granted to me on July 16th, 1901, I have shown a machine for gathering the heads of mantles. My present invention in some of its constructive details may be said to be an improvement upon this general type of machine.

In the accompanying drawings I have shown a machine embodying one form of my invention. But it is to be understood that this drawing is illustrative merely and is not to be taken as representing all forms of machine in which my invention may be embodied.

In the drawing, Figure I is a front view partly broken away showing by way of illustration a machine in which my invention is embodied; Fig. II is a plan view of the machine showing one of the sets of jaws and operating mechanism in horizontal section; Fig. III is a side view of the machine; Fig. IV is a section on line 4—4 of Fig. II; Fig. V is a detail view of the mechanism for discharging or throwing out the mantles after they have been sewed; Fig. VI is a detail view of the device for effecting the needle motion; Fig. VII is a broken away detail view of the needle bar of the machine; Fig. VIII is a longitudinal sectional view of the clutch mechanism; Fig. IX is a transverse sectional view thereof; Fig. X is a detail view of the mechanism for moving the gripper bar for gripping the threads; Fig. XI is a side view of one member of the sets of jaws; Fig. XII is a side or face view of one member of the other set of jaws; Fig. XIII is a sectional view taken on line 13—13 of Fig. XII; Figs. XIV, XV, XVI, XVII show the positions of the parts in the various stages of the sewing operation; and Fig. XVIII shows in diagram the com-

pleted product of the machine. Figs. XIX, XX, and XXI are plan views of the lower intermediate and upper transfer slides, respectively.

The main objects of my invention are to produce a machine in which a number of mantles may be sewed at once and in which the mantle after it is sewed may be readily removed from the jaws.

By referring to my U. S. Letters Patent, above mentioned it will be observed that I have shown therein means for bending the mantle material and for passing a thread through the material while so bent or corrugated. My present machine operates upon the same set of principles and before proceeding to describe the detailed construction of the machine I will set forth the general mode of operation.

Referring for the present to Figs. XIV and XVIII inclusive *a* and *b* represent the movable jaws having elevations and depressions therein after the manner of a corrugation. *c* and *d* represent another pair of movable jaws of similar structure. *e* represents the mantle which is adapted to be bent or corrugated when the jaws co-act with each other as shown in Figs. XV and XVII. The teeth *f* of the jaws *c* and *d*, which jaws together constitute a center toothed member having corrugations on opposite sides thereof, are slotted as shown at *g* for the passage of the needle, and in addition are provided with suitable springs shown herein as leaf springs *h*, which springs serve to push the thread or shirring strings out of the slots *g* after the mantle has been shirred.

In Fig. XI I have shown in face view one of the outer jaws. This outer jaw *a* has a slot *i* therein, but as these jaws move away from the mantle and do not carry the mantle, it is not essential that they should be provided with springs *h*. The office of these springs *h* is to aid the operator in removing the mantle from the toothed center member constituted by the jaws *c—d*. I have found in operating the machine forming the subject-matter of my patent above mentioned, that inexperienced operators sometimes have difficulty in removing the mantle from the toothed center member *k* shown therein, as the thread is liable to

catch in the slots through which it has been run. In the present instance, however, the springs h serve to obviate this difficulty.

The operation of this machine, so far as bending or corrugating the fabric is concerned, is in all essential respects the same as the machine shown in and forming the subject matter of my said patent, so that the specific operation thereof need not be described here, except to state that the center member is made in two parts which are movable with respect to each other.

In Fig. XIV the jaws are shown separated. In Fig. XV they are shown as clamping the mantle. In Fig. XVII the parts are shown in the position which they assume while the thread j is being drawn through the mantle; and in Fig. XVIII the completed open-mouthed structure is shown.

Having given briefly the general object and purpose of the machine I will now proceed to describe the detailed construction thereof.

The frame-work of the machine is indicated by the letter k . This frame-work supports all the operating parts and is provided with a front guide-bar l and a rear guide-bar m . The jaws a and b are carried upon the slides which operate on these guide-bars. The jaw a is carried upon the slide c' . The jaws d and e are carried stationarily upon the frame-work of the machine, that is to say, the said jaws are stationary in position on the machine, but each jaw is mounted upon a spring arm; the jaw d being carried upon a spring arm d' , and the jaw e being carried upon a spring arm c' . These springs hold the jaws in position, back to back, so that they constitute a center member toothed on opposite sides. These jaws c and d are adapted to be spread apart by a slide or spreading means c^3 , so that they will assume the position shown in Figs. XV and XVII at the proper time as will be explained. The jaw a is carried upon a spring arm a' carried upon a slide c' . The jaw b is carried upon a flexible arm c^4 carried upon a slide c^5 . The jaws a and b are adapted to be moved inward towards the faces of the jaws $c-d$, after the said jaws have been positioned for operation. This inward movement is accomplished by the beveled face of the slide c^6 acting upon the jaw b , and the beveled face of the slide c^7 acting upon the jaw a as will be explained.

There are several groups or sets of jaws. In the present instance I have shown three, A, B and C. These sets of jaws are all similar and similarly operated. The movements of the various parts of the machine are effected and initiated by means of a suitable main cam shaft e' , having thereon a set of cams for bringing about the various operations. The movements of the slides c' and c^5 of the various sets is effected by means of a rod e^2 .

This rod e^2 passes rigidly through each of the slides $c'-c^5$ of the several sets and slides in the slots of the slides c^3 , c^6 and c^7 of the several sets. Suitable arms e^3-e^3 are pivoted at e^4 on the frame-work of the machine and are connected to the rod e^2 . These arms e^3 are provided with bowls e^5 which operate in a cam slot e^6 of the cams e^7 . As the cams e^7 rotate the upper ends of the arms e^3 will be swung forward, thereby moving the outer set of jaws $a-b$ forward to position them for co-operation with the center toothed member or double set of jaws $c-d$. This positioning is not shown in the drawings, but it will be understood that the slides c' and c^5 move forward until the jaws $a-b$ are opposite the corrugated jaw-faces $c-d$. It will be understood that the jaws after they are positioned for action are set into action as follows:

The slide or separating means c^3 enters between the two portions $c-d$ of the center corrugated member and spreads them apart, and the slides c^6-c^7 press the jaws $a-b$ inward to co-operate with the corrugated jaw portions $c-d$. This movement will be obvious from an inspection of Figs. XIV and XV, wherein the jaws are shown in their different positions. The slides c^3 , c^6 and c^7 receive their movement as follows:

The rod e^8 is rigidly secured to the slides c^3 , c^6 , c^7 of each set of jaws. This rod is connected to suitable arms e^9 which are pivoted at e^{10} in the frame-work of the machine and are provided with bowls e^{11} which enter slot e^{12} in the cams e^{13} . The cam e^{13} is so timed with respect to the cam e^7 that the slides e^3 , e^6 , e^7 are caused to move forward after the jaws $a-b$ have been positioned for action.

The needle motion shown in the present machine is as follows: The needles o are arranged in pairs upon a needle-bar o' . The needle-bar o' rises and falls in suitable guides o^2 being actuated by the links o^3 pivoted thereto and to arms o^4 (see Figs. IV and VI), which arms are pivoted at o^5 and are pivotally connected by the link o^6 to an arm o^7 pivoted at o^8 and provided with a bowl o^9 adapted to co-operate with cams e^{14} on the main cam shaft e' . A rising and falling motion is thus imparted to the needles. The needle-bar in its movement is adapted to contact with the cross or stop bar f' carried upon suitable guides f^2 , surrounded by spiral springs f^3 . These cross-bars are adapted to receive the impact of the needle bar.

Suitable guides d^2 and d^3 are provided for the double purpose of aiding in guiding the needle if necessary and guiding the mouth or head of the mantle onto the oppositely corrugated center-member.

Having described the operation of the jaws and the needle motion, I will now proceed to describe the operation of the threadder so-called. By a threadder I mean to include any automatic means whereby the thread is

caused to be passed through the needle eyes. In the present instance I have shown means for passing the ends of the thread in opposite directions through the eyes of the pairs of needles. In the machine shown in the accompanying drawing I employ thread loops instead of a continuous length of thread. This thread loop j is clearly shown in Figs. XV, XVII and XVIII. Extending across the machine are bars $s-s'$. These bars are adapted to support the thread loops, the bights of the loops being thrown across said bars. A bar s^3 is adapted to lie in the space between the bars $s-s'$ in order to grip the loops. This bar s^3 is carried upon the arms s^4 pivoted at s^5 to the frame of the machine and having connected thereto a link s^6 . This link s^6 is shown in the present instance as slotted to surround the shaft e' and is provided with a bowl s^7 adapted to coöperate with a cam s^8 on the cam shaft e' . The parts just described together with a spring not shown constitute the actuating means for the bars s^3 to cause it to ascend or descend to grip the bights of the threads j .

The free ends j' and j'' of the threads are laid in hooks $v-v'$ carried respectively upon slides v^2-v^3 . These slides v^2-v^3 extend transversely of the machine over the jaws and are adapted to receive a reciprocating movement. This reciprocating movement may be variously imparted to the said slides. In the present instance I have shown three slides, one above the other. The lowermost of these slides v^4 is provided with straight slots extending in the direction of movement of the slides which actuate the crimping jaws. The slides themselves are carried upon slides v^5-v^6 at each end of the machine, which slides are provided with pins v^7 passing through all of the slots of the lateral or transverse slides $v^2-v^3-v^4$.

The slides $v^2-v^3-v^4$ are slotted longitudinally with slots v^8 so that the said slides are worked upon the said pins. The slides v^5-v^6 are moved back and forth in the machine by links v^9 pivotally connected to the said slides at one end and on the rock shaft or pivotal axis e^4 . These arms v^9 are operated by cams v^{10} so that as the main cam shaft e' revolves the slides carrying the threader hooks will be moved bodily back and forth in the machine to position the said threader for action when the needles have passed through the fabric and are in position to be threaded.

The lowest slide v^{14} carries no hooks and is provided with transverse slots v^{14} . The intermediate and upper slides v^3 and v^2 , respectively, which carry the hooks v' and v , respectively, are provided with the slots v^{11} and v^{12} , respectively. These slots run for a portion of their length transversely of the slides and turn at an angle of 45° near one end. The slots v^{11} turn in one direction and the slots v^{12} in the opposite direction, as

shown in Figs. XX and XXI. When these slides are assembled in the machine, the slots v^{14} , v^{11} and v^{12} partially register so that pins v^{13} pass through each of them and into the slides c^6 and c^7 respectively. These pins v^{13} move freely through the slots v^{14} without in any way interfering with the motion of the slide v^4 . However, with the slots v^{11} and v^{12} , the case is somewhat different. These pins v^{13} shift through the transverse parts of these slots without interfering with the movements of the plates v^3 and v^2 respectively. When these pins strike the parts of these slots which lie at an angle of about 45° to the transverse portion, these plates are shifted to correspond to the change in direction of the slots which movement is allowed by the longitudinal slots v^8 above described.

The motion imparted by the cams v^{10} which move the slides v^5-v^6 to position the threader for action, is so timed with respect to the motion imparted by the cams e^{13} that no lateral motion of the slides v^2-v^3 on each other will take place during the positioning movement, but when the positioning has been effected forward movement of the slides c^6-c^7 will cause motion to be imparted to the plates or slides v^2-v^3 in order to cause the hooks $v-v'$ to approach each other and recede from each other while they are positioned for operation. The detailed operation of the construction will be carefully traced hereinafter.

In order to eject the finished mantles from the machine I provide a suitable roller x which is journaled on the arms x' carried by the frame and is provided with a pinion x^2 meshing with a gear x^3 hung upon a suitable stud on the arm x' .

A ratchet x^4 is rigidly secured to the gear x^3 and is adapted to receive motion from a pawl x^5 carried by a swinging arm x^6 which is pivotally connected by a link x^7 with an arm x^8 pivoted at x^9 working in a cam x^{10} on the main cam shaft e' (see Fig. V). At the moment when the movable jaws and their operating slides are retracted the operating portion of the cam x^{10} rotates the roller x rearwardly throwing the mantles out of the machine. A suitable presser roller x^{11} is carried upon a yoke x^{12} pivoted at x^{13} on the frame of the machine with a spring x^{14} to hold it up to its work.

In Figs. VIII and IX I have shown a suitable clutch for effecting the actuation of the device. This clutch is so arranged that when it is thrown into action it will cause the shaft e' to make one-half a revolution. Mounted on the frame-work of the machine is a sleeve or bushing z which is adapted to rotate freely with the shaft e' which is journaled therein. This bushing is provided with a bolt or clutch member z' which is impelled forward by a spring z^2 and is adapted to contact with pins z^3 on the hub z^4 of the driving pulley z^5 . The

machine may be operated either by hand or by power. I have shown means, to wit, the pulley z^5 whereby power may be applied to the machine.

5 The bolt or tooth z' is provided with a pin z^{30} which is adapted to coöperate with a pair of arms $z^{14}-z^{15}$. These arms $z^{14}-z^{15}$ are pivoted respectively at z^6-z^7 and are geared with each other as by means of segment 10 gears z^8-z^9 . A connection z^{10} may be made with a treadle or other means whereby the clutch may be thrown into action.

The arms $z^{14}-z^{15}$ are provided with cam faces $z^{11}-z^{12}$ with which the pin z^3 coöperates.

15 The mode of operation of the clutch is as follows: When the pin is in the position shown in Figs. VIII and IX on an elevated part of the cam face of one of the arms $z^{14}-z^{15}$ the teeth z' is held back against the pressure of its spring z^2 and the pulley z^5 is free to revolve. When the treadle is pressed down thereby through the connection z^{10} swinging the arms $z^{14}-z^{15}$ apart, the pin z^{30} being no longer held by the arm z^{15} , the tooth z' moves forward into the path of one of the pins z^3 on the hub z^4 of the pulley z^5 . As the pulley z^5 is loose upon the shaft e' and the sleeve z is fast thereon the shaft will thus be coupled up 20 for movement; but as the sleeve z rotates the pin z^3 will run upon the cam z^{12} and when it reaches the highest point of the cam the tooth z' will be withdrawn and the pulley z^5 will thus run freely.

25 The detailed operation of the machine is as follows: The mantles are first placed over the jaws $c-d$ of the crimpers which together constitute the center member of the crimping device and over the rounded end guides d^2 , a roll x^{11} firmly gripping the mantles. The mantles when in the condition in which they are sewed are flattened tubes. These flattened tubes pass between the rollers $x-x^{11}$; as the jaws are substantially vertical, they 30 are substantially at right angles to the axis of the rollers. In order therefore that the flattened tubes may properly engage the jaws it is necessary to impart thereto a quarter twist. Thereupon the movable side jaws advance into position, the threading mechanism being also positioned for operation. The separator for the inside movable jaws of each gang comes forward and at the same time the compressors for the outside movable jaws 35 for each gang come forward. The mantles are thus firmly gripped and the threaders are positioned. The needles now pass through the fabric and passing into the paths of the threader hooks remain stationary for a short 40 space of time, the machine having completed a half revolution and the knockout clutch having operated to stop the machine. Thereupon the operator lays the loops of the thread j in the machine, the ends of the loops lying 45 across the threader hooks $v-v'$ and the loops

of the threader hooks lying across the bars $s-s'$. Further rotation of the machine will cause the gripper bar s^3 to descend gripping the loops of the thread so as to hold the threads in place while the ends are being 50 drawn through the eyes of the needles.

The slides v^2-v^3 now operate to move the threader hooks from the positions shown in Fig. XV to the position shown in Fig. XVI drawing the threads through the eyes of the needles and after the threader hooks have cleared the needles recede as shown in Fig. XVII drawing the thread through the fabric; at the same time the gripper bar s^3 ascends so that the needles draw 55 the loops up to the fabric all as clearly shown in Fig. XVIII which illustrates the finished product. The operations are now reversed, the parts assume the positions shown in Fig. XIV, the springs h operate to throw the fabric out of the corrugations of the center member $c-d$ and the ratchet gear is thrown into action to discharge the mantles from the machine. The stirring strings may now be gathered up, 60 which may be done by hand or by machine and the mantles tied up to form a finished product.

Having described my invention, what I claim and desire to secure by Letters Pat- 65 ent is:

1. In a machine for stirring, gathering or corrugating tubular or like fabrics, the combination of a toothed center member slotted for the passage of a thread, a plurality of 70 movable toothed fabric corrugating jaws co-operating with said center member and having lateral slots therein for the passage of a thread and a spring device carried by the center member for ejecting the stirring string 75 laterally from the slot in the said center member.

2. In a machine for gathering the mouths of tubular or like structures, the combination of a plurality of sets of movable corrugating means, means for moving the same simultaneously, one of each set serving as a center member for the organism.

3. In a machine for gathering the open mouths of tubular or like structures, the combination of a plurality of sets of movable jaws provided with teeth or corrugations, the teeth or corrugations of each jaw being adapted to mesh simultaneously with the teeth or corrugations of another jaw, a plurality of the said movable jaws of the said sets being located within the periphery of the said open mouth of the tubular structure when the tubular structure is in position on the same.

4. In a machine for sewing the heads of mantles or like tubular structures the combination of a gang of individual sets of means for corrugating a tubular or like structure, a series of needle mechanisms, one of which

cooperates with each set, the said needles being carried by a common carrier and a common operating means for producing harmonious relative movement between the 5 needles and the individual parts or members of the gang.

5. In a machine for gathering the mouths of tubular or like structures, the combination of a gang of sets of mouth-gathering means, a gang of needles coöperating individually with individual sets of the mouth-gathering means and carried by a common movable support, and means connecting the needles and mouth-gathering means adapted 10 for bringing about harmonious action between the parts.

6. In a machine for gathering the mouths of tubular or like structures, the combination of a series of means for corrugating or 15 gathering the mouths of a series of tubular or like structures including means for actuating the same, needle mechanisms with means for moving the said needle mechanisms subsequently to the operation of the corrugating 20 means, threader mechanisms and means for operating the threader mechanisms subsequently to an operative movement of the 25 needle mechanisms, the said gathering means, needle mechanisms and threader mechanisms 30 and their actuating mechanisms mutually co-operating to form a unitary operative structure.

7. In a machine for gathering the mouths of tubular or like structures, such as mantles 35 the combination of a series of sets of means for gathering or corrugating the mouths of tubular structures, needle mechanism having individual members adapted to sew the said tubular structures, and means for drawing 40 said tubular structures from the machine, the said means being common to all the sets of corrugating means.

8. In a machine for sewing mouths of tubular or like structures, the combination 45 of mouth gathering means, sewing means, threading means and means for arresting the movement of the thread during the operation of the sewing movement.

9. In a machine for sewing the mouth of 50 tubular or like structures, the combination of a center member corrugated or toothed on opposite sides thereof and normally positioned for operation, a plurality of corrugated or toothed members adapted to co-operate with the said center member, but 55 normally out of operative position, and means for imparting a sliding movement to said last mentioned members to position them for operation and for moving them into 60 a closed position to effect the corrugation of the tubular or like structure.

10. In a machine adapted to gather and 65 sew the mouths of a series of mantles all at once and at one operation, the combination of

a gang of sets of mouth-gathering means with 65 means for effecting the simultaneous operation thereof and sewing means adapted to coöperate therewith, and mantle withdrawing means common to the mouth-gathering means. 70

11. In a machine adapted to gather and sew the mouths of a series of mantles all at once and at one operation, the combination of a gang of mouth-gathering means with 75 means for effecting the simultaneous operation thereof and sewing means adapted to coöperate therewith, and threading means including means for simultaneously operating the threading means.

12. In a machine for gathering and sewing 80 the mouths of a series of tubular structures all at once and at one operation, the combination of means for gathering the mouths of the said tubular structures, said means also constituting supports for the said tubular 85 structures, sewing means, and a means common to all of the supports for maintaining the said tubular structures in position.

13. In a machine for sewing the heads of a number of mantles all at once and at one 90 operation, the combination of means for gathering the mouths of mantles and passing a needle through the said gathered mouths including means for effecting a pause in the action of the machine and means for effecting 95 the passage of the threads through the gathered mouths during a subsequent period of operation of the machine.

14. In a machine for sewing mantles, the combination with mouth-gathering mechanism and sewing mechanism, of actuating mechanism for the said two mechanisms, comprising in its structure means for first operating the mantle-mouth gathering mechanism and then effecting the operation of the 100 sewing mechanism, after the mantle-mouth gathering mechanism has been actuated to gather the mouth of the mantle and a stop mechanism for the needle mechanism-operative to bring about a pause in the action of 105 the machine.

15. In a machine of the character described, the combination of a series or gang of gathering means adapted to gather the mouths of the mantles, a series or gang of 115 needle mechanisms, an operating mechanism common to the gathering mechanisms and needle mechanisms, means for causing a pause in the movement of the needles and means under the control of the operator for 120 starting the machine into action.

16. In a gang machine for gathering the mouths of several tubular structures all at once and in one operation, the combination of a series of sets of corrugating jaws and 125 means for maintaining the tubular structures in position with respect to the said jaws, the planes of operation of the said jaws being

angularly disposed with respect to the plane or planes of operation of the means for maintaining the tubular structures in position.

17. In a sewing machine, a plurality of 5 eyed needles, means for operating the same in combination with needle threading mechanism comprising means for passing different

portions of the same thread in opposite directions through the eyes of the needles to effect the threading operation.
